UNITED STATES PATENT OFFICE.

ELIOT E. FORD, OF BLOOMFIELD, NEW JERSEY.

VENDING MACHINE.

Application filed March 30, 1921. Serial No. 456,853.

This invention relates to an improved coin controlled machine, the invention providing a lock which is adapted to be smoothly operated on the depositing of a coin of predetermined size and thickness and without perforations, such coin operating details of the lock to permit the operation thereof, the invention being designed to prevent the passage into the machine, and insuring the return, of any coin or its equivalent that is not of the proper diameter, not of the proper size, or that has perforations or inequalities in it, for instance, slugs, washers or rings.

The invention is illustrated in the accompanying drawings, in which Figure 1 is a back view of the lock. Figure 2 is a front view of the lock with the front plate removed. Figure 3 is a perspective view of the coin slide of the lock. Figure 4 is a perspective view of the inside of the back plate. Figure 5 is a perspective view of the front plate. Figure 6 is a perspective view of the latch of the coin slide and its supporting spring. Figure 7 is a section taken on line 7-7 in Figure 1. Figure 8 is a partial section taken on line 8-8 in Figure 2, and Figure 9 is an enlarged sectional view showing in detail the construction of an arresting stud used in conjunction with the coin slide.

The lock includes a casing formed of a front plate 12 and a rear plate 13, one of the plates, as the plate 13, being recessed inside to form a space or slide-way through which the coin slide 14 moves, the coin slide having a recess 15 which is adapted to receive a coin, and when the coin slide is in its normal position this coin recess is in line with an insertion slot 16 by means of which the coin is inserted.

The coin slide is moved by an arm 17, usually by having its head 18 arranged in a recess 19 in the slide. The arm 17 is arranged on the flattened part 20 and a short shaft 21 projects through the front of the casing and is operated by a suitable handle. The arm 17 is normally held against movement by a latch 23 which projects through the back plate of the lock, as will be seen more particularly from Figures 1 and 8.

The latch is fastened on the free end of the spring 24 which is secured as by a rivet 25 and near its secured end has a stud 26, which stud normally projects slightly within the coin recess 15 of the coin slide and

has a rounded end so that the coin, on its insertion, pushes the stud out, and the latch pin 23, being on the free end of the spring, is moved out so as to release the arm 17, 60 and consequently the slide, if the coin is of the required thickness. The space for the coin to go in between the two plates is made the same as the thickness of a predetermined coin, for instance, a nickel, and nothing 65 thicker can be inserted, but if anything thinner is put in it will not be thick enough to push the stud 26 out; therefore the latch is not entirely withdrawn and the slide can not be moved. This forms a positive means 70 to prevent the movement of the lock by a thin slug or washer.

To regulate the movement of the slide according to the diameter of the coin I provide a lock 27 which is pivoted, as at 28, 75 adjacent to the coin receiving slot 16 and has a hooked end 29 which is preferably notched, as at 30, to receive the point 31 on one edge of the recess 32. The contact face 33 of the lock is engaged by the coin and swings the lock against the influence of the spring 34 which is inserted to make the operation of the lock positive and not entirely dependent on gravity.

If the coin is too thick in diameter it will 85 swing the lock up so that the hooked end 29 will engage the latch at 35 above the recess 32 and the slide can not be moved far enough, nor any delivery mechanism attached thereto be moved far enough, to insure the delivery of any goods.

If the diameter of the coin is too small the hooked end 29 will engage the part 31 of the slideway but if the coin is a coin of the proper diameter, the hooked end will 95 be swung up to the position shown in Figure 2, and, being in line with the recess 32, the slide can be moved to its limit of movement in a forward direction, thus insuring a complete movement of whatever delivery 100 apparatus is connected to the lock.

The back plate is provided with an ejecting opening 36, and to eject the coin there-through I provide an ejecting stud 37, which is normally held in place by the action of the spring 38 to which it is attached, which spring is in turn fastened by a rivet 39 to the casing. The ejecting stud engages the edge of a coin when its rear edge passes over the shoulder 40 of the recess 41 in the front plate, which is opposite the edge of the ejecting opening and the coin is thus shot through 110

into a suitable receptacle or into the bottom of the box.

To guard against perforated articles, such as washers or rings, I provide an arresting stud 42 which is arranged to pass through the spring 38, as will be seen from Figures 7 and 9, and is fastened to the spring 43 which normally presses it inward so that its end enters the recess 41. The ends of the 10 ejecting stud and the arresting stud are rounded or tapered, as at 44 in Figure 9, and the rear face of the arresting stud is usually recessed, as at 45, so as to be engaged by the inner edge of the perforation in a 15 slug or washer 46, which will be seen clearly from Figure 9.

Normally both studs are pressed outward because they are engaged by the slide, as will be seen from Figures 2 and 7, but when the 20 slide is moved forward, even if the slug is of the proper thickness, both studs will enter into the perforation in the coin, being snapped into place by the springs to which they are fastened, and the inner edge of the 25 perforation will be engaged by the arresting stud 42 and the slide can not complete its movement, which complete movement is necessary for the operation of the delivery mechanism. Then when the operating handle is turned back the slug or washer will be presented again at the insertion slot, because on its return it engages first the ejecting stud, its tapered edge forming a little 30 cam surface which pushes it back and it carries with it the spring 43, and consequently the stud 42, far enough so that the tapered face 44 of the arresting stud will also be engaged and slid back to the position shown 35 in Figure 7. These inclined faces also provide for these studs being pushed back when they engage the rear edge of the coin recess 40 15 in the slide 14.

There is thus an adequate security against any fraudulent operation of the lock by a 45 coin that is too large in diameter, by one that is too small in diameter or by a perforated slug, such as a washer.

I claim:

1. A lock for a vending machine, the lock comprising a casing consisting of a back 50 plate and a front plate being spaced apart to form a slideway between them, a slide in the space, the slide having a recess for a coin, the front plate having an insertion slot for the coin, the back plate having an ejection opening, a spring plate having an ejection pin on its end and normally pressed by the spring in the path of the slide and being engaged by the slide when the slide is in its normal or initial position, a second spring 55 normally resting on the first spring and having an arresting stud on its free end, said stud passing through the first spring whereby the arresting stud can be moved independently of the ejecting stud, the wall opposite said studs being recessed said recess having a shoulder opposite the ejecting stud, whereby a coin can be dropped through the 60 ejection opening.

2. A lock for a vending machine, the lock 70 comprising a casing consisting of a back plate and a front plate being spaced apart to form a slideway between them, a slide in the space, the slide having a recess for a coin, the front plate having an insertion slot 75 for the coin, the back plate having an ejection opening, a spring plate having an ejection pin on its end and normally pressed by the spring in the path of the slide and being engaged by the slide when the slide is in its 80 normal or initial position, a second spring normally resting on the first spring and having an arresting stud on its free end, said stud passing through the first spring, whereby the arresting stud can be moved independently of the ejection stud, the wall opposite said studs being recessed, said recess having a shoulder opposite the ejecting stud, 85 whereby a coin can be dropped through the ejection opening, both studs being tapered 90 toward the front at their ends, the rear face of the arresting stud being recessed.

In testimony that I claim the foregoing, I have hereto set my hand, this 28th day of March, 1921.

ELIOT E. FORD.
